UNITED STATES PATENT OFFICE.

RALPH ALEXANDER GAILEY, OF GARFIELD, WASHINGTON.

HEATING-STOVE.

1,175,254.

Specification of Letters Patent. Patented Mar. 14, 1916.

Application filed January 9, 1915. Serial No. 1,362.

To all whom it may concern:

Be it known that I, RALPH ALEXANDER GAILEY, a citizen of the United States, residing at Garfield, in the county of Whitman and State of Washington, have invented certain new and useful Improvements in Heating-Stoves, of which the following is a specification, reference being had to the accompanying drawings.

10 This invention relates to an improved heating stove, and has for its primary object to provide an improved stove construction in which wood is used as fuel, whereby all of the heat components may be withdrawn 15 from the smoke as it arises through the stove drum and passes into the flue or outlet.

The invention has for a more particular object to provide an improved stove of the above type embodying a plurality of air 20 flues or passages around and about which the flame and smoke are adapted to circulate whereby the air in said passages draws practically all the heat out of the smoke, and the creosote becomes crystallized and is deposited 25 upon the walls of said passages.

The invention has for still another object to provide a door in the back wall of the stove whereby the crystal deposits may be periodically removed and the walls of the 30 passages cleaned, and the means carried by the door for effecting an air tight closure of the same against the spaced air flues.

It is an additional general object of my invention to improve and simplify the construction of stoves of the above type, and to obtain a maximum heating capacity in the 35 operation of such stoves, from a minimum consumption of fuel.

With the above and other objects in view, 40 my invention consists in the novel features of construction, combination, and arrangement of parts to be hereinafter more fully described, claimed, and illustrated in the accompanying drawing, in which,

45 Figure 1 is a front elevation partly in section, of a heating stove embodying my invention in its preferred form; Fig. 2 is a rear elevation thereof; Fig. 3 is a side elevation partly in section; and Fig. 4 is a 50 section taken on the line 4-4 of Fig. 3.

Referring in detail to the drawing, 5 designates the stove drum which may be of any preferred form, construction, and capacity. This drum is supported by means of the usual legs 6.

7 designates the smoke outlet pipe or flue

leading to the chimney, and 8 the usual feed door mounted in the front wall of the stove at its lower end.

Above the feed door 8 and the fire pot 60 proper of the stove, a plurality of obliquely inclined passages or flues 9 are arranged. As clearly shown in Fig. 1, these flues extend across the entire width of the stove and open at their opposite ends through the respective side walls thereof. Each of the air flues 9 is constructed of sheet metal, and alternate flues are secured along one of their longitudinal edges to the front wall of the stove drum while the remaining flues are secured 70 at their opposite longitudinal edges to the rear wall of said drum. In the illustrated construction, I have shown five such air flues, though it is to be understood that a greater or less number of the same may be 75 provided in accordance with the capacity of the stove and the size of the apartments it is designed to heat. In the drawing, it will be noted that the upper and lower flues and the central flue are secured to the front 80 wall of the stove drum. The other two flues, at their rear edges and at their ends, are secured to the back wall of the drum for a purpose which will be later referred to. These flues are properly spaced apart, and 85 the other or free ends of the flues are spaced from the contiguous walls of the stove, whereby a circuitous smoke passage indicated at 10 is produced. This passage, at its upper and lower ends, communicates at the 90 back or rear of the stove with the spaces above and below the series of flues, respectively. The lowermost air flue is constructed of comparatively heavy metal, as it is disposed for direct contact by the flame 95 and is, therefore, subjected to the most intense heat. The metal sheet of the next air flue is slightly thinner, and the walls of the remaining flues decrease in thickness to a corresponding degree.

100 The rear wall of the stove drum is provided with an opening indicated at 11, adapted to be closed by the hingedly mounted door 12. The door 12 is provided upon its inner face with the spaced obliquely inclined beads or ribs 13. These ribs or beads are adapted to fit tightly into the open rear edges of the flues 9 which, as above stated, are fixed at their ends to the rear wall of the stove. Thus, said flues are securely 110 closed and all possibility of the escape of air therefrom into the smoke passage, is pre-

cluded, while, on the other hand, smoke cannot enter said flues between the flue walls and the door 12.

In the operation of my improved stove, 5 the wood is placed in the fire pot and ignited. The air passes into the lower open ends of the flues 9 and upwardly through the same. It is apparent that, if desired, pipes may be suitably connected to the upper 10 ends of the several inclined passages and extended to different apartments of the building to convey the heated air thereto. The smoke arising from the fuel passes to the back of the stove and around the lower air 15 flue 9, thence upwardly against the walls of the second air flue and forwardly to the front of the stove, then again backwardly and around the next flue, until the smoke finally enters the upper portion of the stove 20 at the back thereof and is carried off through the smoke pipe 7. In this circuitous passage of the smoke, the air passing through the several flues 9 becomes highly heated, and practically all of the heat 25 components is drawn from the smoke so that the volume of the latter is reduced and the smoke may pass off through a comparatively small outlet. As the heat is withdrawn from the smoke, the latter being reduced in volume, 30 travels more and more slowly so that all comparatively heavy particles therein settle upon the walls of the air flues. The creosote in the wood is also crystallized. This creosote and other foreign matter may 35 be periodically removed from the walls of the air flues and said flues thoroughly cleaned by opening the door 12 and scraping the flue walls. In actual practice, it has been demonstrated that two rooms, having 40 4560 cubic feet of space, may be comfortably heated during weather of about 20° Fahrenheit with a consumption of one cord of pine wood for sixty days. It is, thus, obvious that my improved stove may be 45 very economically operated. The smoke outlet pipe does not become highly heated, because, as above stated, practically all the heat is withdrawn from the smoke before it enters said pipe and, in fact, it is possible, 50 during the operation of the stove, to place the hand upon the smoke outlet pipe without pain. In the test operation above referred to, it was found that, in about three weeks, the space between the air flues became 55 choked with deposits of creosote. These smoke passages and the walls of the

air flues should, therefore, be cleaned weekly, in order to obtain the best results.

From the foregoing description, taken in connection with the accompanying drawing, the construction, manner of operation, and 60 several advantages of my invention will be clearly and fully understood.

In the use of wood burning stoves as heretofore constructed, the said stoves consume comparatively large quantities of wood, and 65 it has been my primary purpose to produce a stove construction whereby substantially all of the heat units will be advantageously utilized, and the consumption of fuel correspondingly reduced. 70

It is obvious that the stove structure may be variously modified to conform to particular conditions or circumstances, and I do not, therefore, desire to be limited in putting my invention into practice to the particular combination and arrangement of the several elements, as illustrated in the accompanying drawing; but reserve the privilege of resorting to all such legitimate changes as may be fairly embodied within 80 the spirit and scope of the invention as claimed. 75

Having thus fully described my invention, what I desire to claim and secure by Letters Patent is:—

The herein described heating stove including a drum, a plurality of equidistantly spaced inclined air flues of uniform area opening at their ends through the opposite side walls of the drum, one of the longitudinal edges 90 of the alternate flues being secured to the front wall of the drum and the other edges of said flues closed and spaced from the rear wall of the drum, the remaining flues being secured at their ends and at their rear edges 95 to the rear wall of the drum and closed at their forward edges and spaced from the front wall of the drum, a clean-out door mounted in the rear wall of the drum, said latter flues being open across the door opening, and a plurality of obliquely inclined ribs on the inner face of said clean-out door to fit within the openings of said flues and effect an air-tight closure between the same and the door. 100

In testimony whereof I hereunto affix my signature in the presence of two witnesses.

RALPH ALEXANDER GAILEY.
